UNITED STATES PATENT OFFICE.

AUGUST H. OPPERMANN, OF INDIANAPOLIS, INDIANA.

DESIGN FOR A COMBINED ELECTRIC-LAMP BRACKET AND CONVENIENCE OUTLET.

Application filed September 29, 1926. Serial No. 19,202. Term of patent 7 years.

To all whom it may concern:

Be it known that I, AUGUST H. OPPERMANN, a citizen of the United States, residing at Indianapolis, in the county of Marion and State of Indiana, have invented a new, original, and ornamental Design for a Combined Electric-Lamp Bracket and Convenience Outlet, of which the following is a specification, reference being had to the accompanying drawings, forming a part thereof.

In the drawings Figure 1 represents a side view of a combined electric lamp bracket and convenience outlet showing my new

design; Fig. 2 is a top plan, partially broken away, of the principal portion of Fig. 1 showing the design on the top thereof; and Fig. 3 is a section on the line 3—3 on Fig. 1 showing the design of the front of the base portion of the article.

I claim:

The ornamental design for a combined electric lamp bracket and convenience outlet, as shown.

In testimony whereof, I affix my signature on the 24th day of September, 1926.

AUGUST H. OPPERMANN.
